DB-305.

OR D11,229 EX

DESIGN FOR DOOR-KNOBS.

Specification forming part of Design No. 11,229, dated June 3, 1879; application filed May 10, 1879.
[Term of patent 7 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONN.

DESIGN FOR DOOR-KNOBS.

Specification forming part of Design No. **11,229**, dated June 3, 1879; application filed May 10, 1879.
[Term of patent 7 years.]

To all whom it may concern:

Be it known that I, RODOLPHE CHRISTESEN, of the city and county of Hartford, and State of Connecticut, have invented a new and useful Design for Door-Knobs; and I do hereby declare that the following specification, taken in connection with the accompanying photographic illustration, forming a part of the same, is a full, clear, and exact description thereof.

The novel design hereinafter described is adapted to the face of a door-knob, and possesses the characteristic feature of being in the Japanese style of ornament.

As shown in the accompanying illustration, the face of the knob is partially surrounded by a wide ornamental border, A, in imitation of marquetry, the ends of which abut against a

curved band, B. Between this band and a plain narrow edge band, a, is located a section of "diaper" ornament, C, composed of triangular figures. The central portion, D, of the face of the knob presents a mottled appearance, and upon it are arranged branches of a shrub which bears leaves and a flower.

The design may be cast in relief or engraved, and is adapted to a knob having a convex, flat, or concave face.

What I claim, and desire to secure by Letters Patent, is—

The Japanese design for the face of a door-knob, substantially as described and shown.

RODOLPHE CHRISTESEN.
